SEWING-MACHINE FEEDING MECHANISM.

1,176,444.

Specification of Letters Patent. Patented Mar. 21, 1916.

Application filed June 27, 1914. Serial No. 847,589.

To all whom it may concern:

Be it known that I, CHRISTIAN H. T. HAGELSTEIN, a citizen of the United States, residing at Dorchester, in the city of Boston, 5 in the county of Suffolk and State of Massachusetts, have invented certain new and useful Improvements in Sewing-Machine Feeding Mechanism, of which the following is a specification, reference being had therein to 10 the accompanying drawing.

This invention relates to sewing machine feeding mechanism, and more particularly to an operative member or feed dog, with mechanism for actuating it in opposition to 15 a resilient work clamping member or presser-foot for advancing the work between the formation of stitches in sewing machines of various types.

For convenience the present invention is 20 shown as applied to the type of sewing machine illustrated in my previously issued Patent No. 1,009,408, although the present improvement might obviously be otherwise employed.

25 An object of the present improvement is to generally improve the construction and operation of such a sewing machine feeding mechanism. As the speed of a sewing machine is increased beyond certain limits, the 30 objectionable results of vibration become more and more apparent and troublesome.

An object hereof is to render the feeding mechanism more smoothly running and, therefore, quieter, so as to permit an increase 35 in speed without sacrifice of the other desirable qualities.

Another object is to reform the actual movement of the under feed dog or block, so as to give more efficient feeding action.

40 Further objects hereof will be elucidated in the hereinafter following description.

To the attainment of these objects referred to, the present invention consists in the novel mechanisms, parts, combinations, 45 arrangements and other features herein shown or described.

First will be described an illustrative embodiment of the present improvement and thereafter the novel features will be pointed 50 out in the claims.

In the accompanying drawings forming a part hereof, Figure 1 is a plan view of so much of the interior portion of a buttonhole finishing machine embodying the present improvement as is essential to the description

thereof. Fig. 2 is a left elevation of the same parts, also showing a portion of the work plate, the presser-foot and the work between them. Fig. 3 is in the nature of a diagram showing the cycle of movements of 60 the feed block.

The fixed parts of the machine may include a work plate 10, frame part 11, shaft bearings 12, 13, etc.

The main shaft, or one of the main shafts, 65 15 is shown as extending horizontally longitudinally of the machine supported in the bearings 12, 13, and driven by pulley 16 and belt 17. A counter-shaft 20 is shown supported in the same blocks or bearings 12, 13, 70 and this shaft may be driven in any suitable manner, for example, by means of the equal gears 21, 22.

The work plate 10 is apertured to receive the feed block or dog 25, and above and opposed to the work plate and feed block is the presser-foot 23, normally held down upon the work by a yielding contrivance 24 of any ordinary form.

The feed block 25 is shown supported 80 upon a carrier 26, which is in the form of an elongated bar set transversely to the length of the machine. The feed block carrier 26 is shown as supported by the mechanism which actuates it, this being a convenient and usual expedient. Thus, the rear end of the carrier 26 is pivoted to the upper end of a swinging arm 27, which, at its lower end, is fulcrumed upon a stud 28. The effective direction of the arm 27 being substantially vertical, its to-and-fro swinging movements guide and move the feed block carrier in a substantially horizontal direction.

It will be understood that the feed block 95 is required to have a cycle of movements involving both horizontal and vertical components, since the advancing or rearward movement of the feed block must be in an upper position in contact with the work, while the 100 return or idle movement of the block is at a lower point.

For effecting the horizontal movements of the feed block and carrier, connections may be employed which operate through the upright supporting arm 27. Thus, a stud 29 is shown secured (adjustably) at an intermediate point in the length of the arm 27, and by means of a cam rod 30 the stud 29 is connected to a cam follower 31, which in turn 110

engages with a cam 32 carried directly on and rotating with the shaft 15. No novelty is predicated on the type of cam and follower shown, as such type is well-known for the 5 purpose of effecting horizontal feed movements, but, as will be hereinafter shown, the contour and timing of the parts embody certain important features. For effecting the up-and-down movements of the feed 10 block and carrier, certain mechanical devices are shown, which, as usual, are located to operate upon the forward end of the carrier. These devices, according hereto, are operated from the shaft 20. At the left end of 15 the shaft is shown a head or crank disk 35, having a stud supporting extension 36. A stud 37 eccentrically located on the crank disk acts as a fulcrum, which, by a short link 38, is connected to a stud 39 mounted 20 on the forward end of the feed block carrier 26.

It will be seen that the horizontal and vertical movements respectively of the feed dog are effected from two continuously and 25 oppositely rotating shafts, which are adjacently parallel and are geared together to rotate in unison. By this arrangement the unbalanced weight of the parts is divided or split up, so as to reduce and, to some extent, 30 counterbalance the effects of momentum at the very high speed at which the parts are to run. Thus, part of the objects referred to are attained.

It will also be seen that a continuously 35 rotating crank of short throw is used for raising and lowering the feed block, so that the same smooth continuity of up-and-down movement is attained that obtains with the reciprocating crosshead of a steam engine. 40 This also furthers the objects of the present improvement. Therefore extreme ease of adjustment is secured. The stud 29 adjusts vertically in a usual manner for varying the extent of horizontal feed movement; while 45 the crank parts 35, 36, 37, afford a novel, simple and efficient adjustment of vertical movement.

The described mechanism does not perform the ordinary four-motion operation, 50 but is such as to give to the feed block a novel action and function. The usual four-motion feed involves a purely or substantially horizontal advance movement or feed movement of the feed block throughout its 55 feeding action, followed by a lowering and a return movement and a lifting between the successive feed movements. In the present invention, on the contrary, the movements are quite different and may be as illustrated 60 by the diagram, Fig. 3. This diagram shows the feed block in four positions. The path of movement is illustrated on the diagram with respect to the upper left-hand corner of the block. The initial position, 65 indicated by *a*, is shown in full lines, and

the second, third and fourth positions, *b*, *c*, *d*, are shown in dotted lines. The advance movement of the feed block, during which the actual feeding is effected, is represented by the curved line, *a*—*b*. This is substantially the arc of a circle, which, if continued, would first rise from the point *a* and afterward descend. The feed movement, however, is cut off at the point *b* during the ascent of the feed block. In consequence 75 thereof the feed block is constantly rising during its feed movement. The point *b* terminates the feeding movement, and immediately the block is dropped to the point *c*, followed by the return movement *c*—*d* 80 and the relifting of the block from *d* to *a* for a repetition of operations. This described operation is of great utility in securing the stated object of rendering the feeding action more efficient. At the very 85 high rate of speed of the parts the rising movement of the feed dog practically strikes a blow at the underside of the resilient presser-foot and the momentum of the parts would frequently tend to cause the presser-foot to slightly lift. With a horizontally traveling feed block the continued lifting of the presser-foot under momentum might very readily reduce the pressure between the parts, so as to loosen the grip of the feed 90 block upon the work so that the feed would not be so accurate and reliable as desired. With the present construction, however, absolutely reliable coöperation between the feed block and the presser-foot is secured 100 because, as will be perceived by the diagram, Fig. 3, the feed block constantly rises during the advance or feed movement, so as to follow up and maintain the pressure against the presser-foot. Moreover, the curved path 105 of the feed block from *a* to *b* involves a gradually decreasing rate of lifting during the feed action, and this would be in entire harmony with the tendency of momentum to lift the presser-foot against the increasing 110 resistance of the resilient device 24.

Referring now more in detail to the cam and follower device 31, 32, and the crank device 35—37, they will be seen in Fig. 2 to be so constructed as to secure the action indicated in the diagram illustrated in Fig. 3. The cam 32 and the crank 37 reversely rotate, and the arrows designate their direction. The full lines show the parts at the beginning of the feed movement and correspond with the full line of the diagram, position *a*. The dotted lines in Fig. 2 show the position of the parts at the end of the feed movement, corresponding with the point *b* of the diagram. In Fig. 2 the cam 32 is seen to be holding the cam follower 31, and therefore the feed block, at their extreme right-hand position. The crank 37 is shown as positioning the feed block nearly at the top limit of its movement. The continued 120 125 130 135 140 145 150 155 160 165 170 175 180

rotation of the shafts 15 and 20 will simultaneously serve during about one-eighth of a revolution to turn the cam 32 to the dotted position shown, and thereby move the feed block to its extreme left position, and also to lift the crank stud 37 to its dotted position shown, thereby lifting the feed block to the upward extreme of its movement. The feed block having thus traveled from 5 *a* to *b*, the horizontal feed movement ceases on account of the dwell of the cam 32, while the continued rotation of the crank 37 lowers the feed block, swinging it about the upper end of the arm 27 as a fulcrum until 10 it passes to the position *c*. After this, as the crank and cam rotate, an eccentric portion of the cam throws the block again rearward as it completes its downward travel, thus describing the path *c-d*, upon which 15 20 the crank effects the lifting of the block through the path *d-a* while the cam is again idle.

The representation of motion in the diagram, Fig. 3, may be considered as exaggerated, and it will, of course, be understood 25 that the extent of advance movement or feed and the extent of rising during the feed may be larger or smaller as desired or suitable for any particular purpose.

30 It will be seen that there has been described a sewing machine including in combination with the stitching means the following features. The plate 10 is a work supporting member, and this and the 35 presser-foot member 23 are resiliently opposed to each other for mutually clamping the work between them. The movable feed block 25 is adapted to engage and disengage the work, which is clamped between said 40 members. The mechanism for actuating said feed block is adapted to move the block toward the resilient work clamping member throughout its feed movement; and this movement toward the resilient member or 45 presser-foot is at a decreasing speed. The parts 27 to 32 constitute a device for moving the feed block longitudinally in the line of feed. The parts 35 to 39 constitute a 50 crank-operated device for moving it toward and from the resilient work clamping member. Said two devices are so harmoniously timed that the advancing feed movement of the block occurs only at the latter part of the 55 crank-operated lifting movement of the block, that is to say, the movement toward the resilient presser-foot. Said two devices are arranged on two parallel continuously 60 rotating shafts geared together. The feed movement of the block is in the plane of the work or the work support, and the movement toward the presser-foot is transverse to such plane. The element of resilience may be supplied in various ways, for convenience by a spring on the presser-foot carrier as shown. The two shafts 15 and 20

rotate in opposite directions at the same speed, so that the two devices upon those shafts operate harmoniously.

It will thus be seen that there has been described a sewing machine feeding mechanism 70 securing the objects and advantages before recited, and other advantages will be apparent to those skilled in the art. Since many matters of combination, arrangement, detail and other features might be 75 varied without departing from the novel principles involved, no limitation to such features is intended excepting so far as set forth in the appended claims.

What is claimed is:

1. A sewing machine including in combination with stitching means, a work supporting member and a presser-foot member resiliently opposed thereto for mutually clamping the work, a movable feed block 85 adapted to engage and disengage the work which is clamped between said members, and actuating mechanism for giving said block its feed movements and reverse movements and constructed to automatically give 90 said block a movement toward said resilient work clamping member throughout its feed movement.

2. A sewing machine including in combination with stitching means, a work supporting member and a presser-foot member resiliently opposed thereto for mutually clamping the work, a movable feed block adapted to engage and disengage the work which is clamped between said members, and actuating mechanism for giving said block 100 its feed movements and reverse movements and constructed to automatically give said block a movement at decreasing speed toward said resilient work clamping member 105 throughout its feed movement.

3. A sewing machine including in combination with stitching means, a work supporting member and a presser-foot member resiliently opposed thereto for mutually 110 clamping the work, a movable feed block adapted to engage and disengage the work which is clamped between said members, and mechanism for actuating said block comprising a device for moving it longitudinally in the line of feed and a crank operated device for moving it toward and from the resilient work clamping member, 115 said two devices so harmoniously timed that the advancing feed movement of the block occurs only at the latter part of the 120 crank operated movement toward said resilient clamping member.

4. In or for a sewing machine a feed block and mechanism for operating it 125 through feed and return movements and for moving it transversely to the work plane toward the work throughout its feed movement.

5. A sewing machine including in com- 130

- bination with stitching means, a work supporting member and a presser-foot member resiliently opposed thereto for mutually clamping the work, a movable feed block 5 adapted to engage and disengage the work clamped between said members, a continuously rotating shaft, a continuously operating crank device operated from said shaft for moving said block toward and from the 10 work, and means for giving the block its feed and return movements, said crank device and said means so timed that throughout the feed movement the block is moving toward the work at a decreasing speed.
- 15 6. A sewing machine including in combination with stitching means, a work supporting member and a presser-foot member resiliently opposed thereto for mutually clamping the work, a movable feed block 20 adapted to engage and disengage the work clamped between said members, a continuously rotating shaft, a continuously operating crank device operated from said shaft for moving said block toward and from the 25 work, a second shaft, and means for giving the block its feed and return movements actuated from said second shaft, said two shafts geared together to continuously rotate in opposite directions at the same rate, 30 and the connections actuated from said two shafts being so timed that throughout the feed movement the block is moving toward the work at a decreasing speed.
- 35 7. A sewing machine including in combination with stitching means, a work supporting member and a presser-foot member resiliently opposed thereto for mutually
- clamping the work, a movable feed block adapted to engage and disengage the work clamped between said members, two operating 40 shafts geared together to continuously rotate in unison, a device on one shaft for giving feed and return movements to the block, and a continuously moving device or crank on the other shaft for giving the 45 block movements toward and from the work, and the connections actuated from said two shafts being so timed that throughout the feed movement the block is moving toward the work at a decreasing speed. 50
8. A sewing machine including in combination with stitching means, a work supporting member and a presser-foot member resiliently opposed thereto for mutually clamping the work, a movable feed block 55 adapted to engage and disengage the work clamped between said members, two parallel operating shafts geared together to continuously rotate in unison in opposite directions at the same speed, a device on one shaft for giving feed and return movements to the block, and a continuously moving device or crank on the other shaft for giving the 60 block movements toward and from the work, said two devices timed so that throughout the feed movement the block is moving toward the work at a decreasing speed. 65

In testimony whereof, I have affixed my signature in presence of two witnesses.

CHRISTIAN H. T. HAGELSTEIN.
